US00D689118S

(12) **United States Design Patent**
Koh et al.

(10) **Patent No.:** **US D689,118 S**
(45) **Date of Patent:** **** Sep. 3, 2013**

(54) **SUNGLASS**

(75) Inventors: **Juliette Bonghee Koh**, Carlsbad, CA (US); **Keith Larronde Asher**, Carlsbad, CA (US)

(73) Assignee: **Spy Optic Inc.**, Carlsbad, CA (US)

(**) Term: **14 Years**

(21) Appl. No.: **29/396,612**

(22) Filed: **Jul. 1, 2011**

(51) **LOC (9) Cl.** **16-06**

(52) **U.S. Cl.**

USPC **D16/325**

(58) **Field of Classification Search**

USPC D16/101, 300–342, 900; D29/109–110; 351/41, 44, 51–52, 62, 158, 92, 103–123, 351/140–153, 45–46; 2/426–432, 447–449, 2/441, 434–437, 13, 15; D21/483, 659–661; D14/372

See application file for complete search history.

(57) **CLAIM**

The ornamental design for a sunglass, as shown and described.

DESCRIPTION

FIG. 1 is a front perspective view of the sunglass of the present invention showing my new design with the dotted lines not forming any portion of the claimed design;

FIG. 2 is a front elevational view thereof;

FIG. 3 is a side elevational view thereof;

FIG. 4 is a rear elevational view thereof;

FIG. 5 is top plan view thereof; and,

FIG. 6 is bottom plan view thereof.

1 Claim, 3 Drawing Sheets
